UNITED STATES PATENT OFFICE.

NATHANIEL M. ONG, OF YORK, PENNSYLVANIA.

FLEXIBLE STRIKING DEVICE FOR PIANO-ACTIONS.

1,342,029.

Specification of Letters Patent.

Patented June 1, 1920.

Application filed January 14, 1920. Serial No. 351,412.

To all whom it may concern:

Be it known that I, NATHANIEL M. ONG, a citizen of the United States, residing at York, in the county of York and State of Pennsylvania, have invented a new and useful Flexible Striking Device for Piano-Actions, of which the following is a specification.

This invention relates to new and useful improvements in piano actions and an improved flexible striking device therefor.

As heretofore constructed, striking capstans used in connection with player pianos, pianos for mechanical operation, and automatic instruments of the key operated type have been of a complicated nature, or such that a heavy stroke or blow of the key, would result in injury to the parts of the piano action, result in unequalization of the blow instead of softening the same automatically, and also producing a metallic tone in addition to permitting the prolong or co-operating part of the piano action, to become displaced thereby interfering with the playing of the parts and causing friction.

The present invention constitutes a novel improvement for pianos, player pianos and other automatic instruments of this type, in which a prolong or lifter is provided, co-operating with a flexible striking device mounted on the inner end of the key, so that the latter is depressed at its outer end and rocked on its fulcrum, the proper motion will be transmitted to the hammers for the purpose of playing the instrument, the device being such that the touch and stroke will be improved, the flexibility of the device serving to equalize both the touch and stroke and resulting in an automatic softening of the blow so as to prevent injury to the action parts thus producing the delicate human finger touch that is only comparable with hand playing.

A further object of the invention is to provide a device of the above character which will insure long life to the instrument, improve the quality of the tone, and cheapen and simplify the construction of actions. The device further embodies a striking device, which is constructed in a simple and novel manner, so as to be very economically produced from a single section of spring metal in strip form, so as to be readily applied to a key and retained in position, for giving the desired cushioning action which when striking a key with a heavy stroke or

blow, will result in the absorption of the shock or force of the blow, thereby preventing injury to the action parts.

With the above and other objects in view which will appear as the description proceeds, the invention resides in the combination hereinafter described and claimed, it being understood that within the scope of what is claimed, changes in the precise embodiment of the invention shown can be made without departing from the spirit of the invention.

In the accompanying drawings:

Figure 1 is an end elevation of a piano action provided with a prolong or lifter, showing a key having a flexible striking device, constructed in accordance with the invention:

Fig. 2 is an enlarged fragmentary vertical sectional view through the inner end of a key and the flexible striking device applied thereto, the lower portion of the prolong or lifter being shown engaged with the contact portion of the device; and

Fig. 3 is a perspective view of the striking device detached from its co-operating means, and mounted on the inner end of a key, the latter being shown in phantom.

Referring to the drawings in detail in which like reference characters designate corresponding parts throughout the several views, a piano action is designated generally at 10, provided with hammers 11 adapted to strike the strings or other music producing elements of a piano, player piano or automatic instrument employing any one or a number of instruments. The damper is designated at 12 and 13 designates generally the action through which motion is transmitted from the keys to the hammer or hammers. The prolong of the action is designated at 14 and has the lower end thereof resting on the flexible striking device or capstan 15 constituting the subject matter of the present invention.

The keys are designated at 16, and pivot on the fulcrums 17 for actuation in the usual manner, in playing of the instrument. One of the flexible striking devices is mounted on each key, that is, on the upper edge of each, adjacent to the inner extremity thereof and as shown each device comprises a narrow strip of flexible metal, such as spring steel or the like, with proper resiliency and strength, the lower portion 18 thereof being of rectilinear formation and flat and having

one end thereof disposed outermost, curved or bent upon itself as shown at 19, to extend upwardly and rearwardly and formed with a horizontal portion 20 terminating in an upwardly extending portion 21 from which extends a horizontal portion 22 adapted for contact with the lower end of the prolong 14.

The bottom portion 18 is provided at one end with an attaching means adjacent the inner end of the key, in a form of a downwardly bent prong or bur 23 adapted to penetrate the key for securing the device in position. Each device is made of a strip of less width than the width of the key, preferably, and is mounted at a relatively short distance from the inner end thereof, the rectilinear portion 18 forwardly of the prong 23 and intermediately of the length of the portion 18, being provided with an aperture 24 alined with an aperture 25 in the horizontally disposed top portion 20, which is substantially parallel to the portion 18. A fastening screw 26 or the like, passes through the openings 24 and 25 and engages the key 16, the head of the screw serving as a stop to limit the upward movement of the depressible top portion of the device, while permitting the necessary downward movement and giving the desired flexibility, for the purpose of absorbing somewhat the force of a heavy stroke or blow whereby to automatically soften the same and prevent the transmission of the force to the action. It is to be understood that the top portion is normally held in raised position and the screw, in addition to serving as an attaching means, also serves as a guiding means for the flexible top portion of each device. This top portion has movement from the bent or curved portion 19, so as to produce the desired flexibility, and the contact portion 22 is straight or rectilinear transversely but rounded or of oval formation longitudinally as clearly shown in the drawings, thus obviating the tendency to throw the lifter or prolong to either side, which would cause friction or dislodgment, and would thus interfere with the proper playing. The free end of the contact portion 22 is preferably bent downwardly as indicated at 27 to avoid the exposure of a sharp edge or possible contact thereof with the prolong or lifter, and also to give the necessary strength transversely to the contact portion.

Thus, when the key is actuated, the inner end thereof will be raised, the outer end being depressed in the playing, so as to raise the striking device in the contact with the lower end of the prolong 14, to actuate the action. As the device contacts with the prolong, the desired flexibility will be produced by the upper portion, which will be permitted to move downwardly over the screw 26, and thus cushion or soften the

blow. This will result in an improved touch and stroke of the hammer, especially when a heavy stroke is made, the flexibility of the device causing an equalization of the force which will obviate the metallic tone which will otherwise be caused, and generally improve the quality of the tone. It is to be understood that the device can be applied to pianos, player pianos or other automatic instruments of this type, and that changes in the exact form, size and arrangement of the device may be made within the scope of the device claimed.

Having thus described the invention what I claim is:

1. The combination with the action of a musical instrument having a prolong and key for actuating the same; of a flexible striking device mounted on the inner end of the key beneath said prolong, and comprising a bent flexible strip with a lower portion disposed flat against the key and an upper portion movable relative thereto.

2. The combination with the action of a musical instrument having a prolong and key for actuating the same; of a flexible striking device mounted on the inner end of the key beneath said prolong, and comprising a flexible strip, said strip being bent upon itself to provide a lower portion disposed flat against the top of the key throughout the length of said lower portion and anchored to the key and an upper portion diverging upwardly therefrom, means carried by the key and passing through said portion to movably receive the upper portion thereon, said upper portion being provided with a contact part at the free end thereof for engagement with the lower end of the prolong.

3. The combination with the prolong of a piano action and a key for operating said action through the medium of said prolong; of a flexible striking device mounted on a key adjacent the inner end thereof for disposition beneath said prolong, said striking device comprising a single strip of resilient material of approximately the same width as the key and having a prong at one end engaged with the key, said strip being bent upon itself rearwardly to provide a lower portion disposed against the key and an upper portion movable in a flexible limited path with respect thereto, said upper and lower portions being provided with apertures, a screw engaged through said apertures and on which the upper portion is adapted to have limited movement downwardly, and upwardly, said upper portion being provided with a raised part at the free end thereof for contact with the lower end of the prolong.

4. A flexible striking device of the class described, comprising a resilient strip of metal bent upon itself to provide a hori-

zontal lower portion having one end formed with a prong and an upper portion diverging therefrom, said upper portion having a raised part at the free end thereof of a rectilinear formation transversely and rounded formation longitudinally.

5. A flexible striking device of the class described, comprising a resilient strip of metal bent upon itself to provide a horizontal lower portion having one end formed with a prong and an upper portion diverging therefrom, said upper portion having a raised part at the free end thereof of a rectilinear formation transversely and rounded formation longitudinally, said upper and lower portions being provided with apertures adapted to receive a securing member and said upper portion being flexibly movable with respect to the lower portion.

10 6. The combination with a key, of a flexible striking device comprising a relatively inclined resilient strip having a contact portion, and securing means for fixedly mounting the strip on the key, said means serving to limit the vertical movement of the strip, said strip being normally elevated.

20 7. An improved flexible striking device for pianos and the like comprising a narrow relatively thin strip of resilient metal bent upon itself to provide a rectilinear bottom portion formed with means to anchor the same to a key and the bent portion being extended upwardly and rearwardly to provide a horizontal portion and a raised contact portion at the free end thereof, said

horizontal portion and said rectilinear portion each having an aperture, said apertures being disposed in alinement, guiding and securing means disposed through said apertures and permitting depression of the bent 40 portion with respect to the lower rectilinear portion.

8. An improved flexible striking device for pianos and the like comprising a narrow relatively thin strip of resilient metal bent 45 upon itself to provide a rectilinear bottom portion formed with means to anchor the same to a key and the bent portion being extended upwardly and rearwardly in a horizontal position, and a raised contact portion 50 at the free end thereof, said horizontal portion and said rectilinear portion each having an aperture, said apertures being disposed in alinement, guiding and securing means disposed through said apertures and 55 permitting depression of the bent portion with respect to the lower rectilinear portion, said contact portion having a vertical offset at the point of rearward limitation thereof, and being flat transversely and slightly oval 60 longitudinally, the free end of the bent portion being bent downwardly.

In testimony that I claim the foregoing as my own, I have hereto affixed my signature in the presence of two witnesses.

NATHANIEL M. ONG.
